Specification of Letters Patent. Patented Jan. 31, 1922.

Application filed September 18, 1917. Serial No. 192,015.

To all whom it may concern:

Be it known that we, WILLIAM FETZER, JOHN G. FEERES, and OTTO A. ELLIOTT, citizens of the United States, residing at 5 Springfield, Springfield and Marion, respectively, in the counties of Sangamon, Sangamon, Williamson, respectively and State of Illinois, have invented certain new and useful Improvements in Incinerators, of which 10 the following is a specification, reference being had therein to the accompanying drawing.

This invention relates to improvements in incinerators, and is designed more particularly for use in connection with the burning 15 of garbage, city refuse, and the like.

In the burning of garbage, as heretofore practiced, in plants designed to take care of the garbage of towns or cities, the garbage 20 has been deposited usually on grated receiving bottoms and dried and burned. In most instances, the drafts are in an upward direction and are designed to be carried or forced through the piled up garbage. While 25 it has been suggested in the past to employ what is commonly known as the starting grate, and to thereafter rake portions of dried material from the garbage grate on to the fire grate, it has not, as far as at present 30 known to us, been suggested or proposed prior to the present invention to utilize this principle of drying and burning under such conditions as will eliminate or prevent the escape of obnoxious vapors or odors and further 35 the incinerators heretofore suggested have been comparatively complicated, of large proportions, especially in a vertical direction, and have been so constructed as to require expert skill in manipulation.

40 The object of the present invention is to produce an incinerator wherein an effective down-draft may be employed, the heated products of combustion passing over the garbage downward into the down-draft and escaping into the up-take or chimney. A further object of the invention is to provide 45 an incinerator with a plurality of burning grates, a dumping floor on the plane of and intermediate the grates and the stoking 50 opening so positioned that the operator can rake the dried material from the heap onto

either grate for burning thereon. A further object is to provide an incinerator of the above suggested character with proper draft controlling means. Further objects 55 of the invention will be mentioned in the following specification, and will be appreciated by those skilled in this art.

In the accompanying drawings, there is 60 shown one embodiment of the invention in its various details, but it is to be understood that changes and variations may be made without departing from the nature and principle of the depicted structure and invention. 65

In the drawings:

Figure 1 is a front elevation of the incinerator.

Figure 2 is a longitudinal horizontal section through the line 2—2 of Figure 1, looking downward. 70

Figure 3 is a longitudinal vertical section through the line 3—3 of Figure 2.

The furnace comprises substantially four vertical walls, 1, 2, 3 and 4, conveniently 75 stayed and trussed by anchor rods and face braces, as indicated at 5 and 6. The front of the furnace is provided with a centrally disposed opening A having stoking port or ports B, B'. On opposite sides of the center there are openings C, C' for the ash pit and grates, presently to be described. The walls of the furnace are conveniently composed of layers, the inner layer being of refractory material as at D, an interposed 80 layer of insulating material at D' and an outer casing or shielding of masonry as at D''. E represents the floor or bottom of the furnace, and F and F' the fire grates located at the front in opposite corners leaving a 85 material space between. These grates may be of any convenient or recognized form, and are margined at their forward and inner edges by short upstanding curbs f. The height of these curbs above the grate bars 90 may be approximately six inches. The inner wall of each curb is sloping for purposes presently to be described. The stoking opening A flares at its inner end to permit a 95 wide lateral sweep of the stoking iron. 100

Arranged centrally of the furnace and at the extreme rear is a down-draft port G

bounded by a curb *g*, suitably barred and extending into a tunnel or flue *G'*. This tunnel extends outwardly to an up-take or chimney which may be located at any convenient point beyond the furnace wall. The tunnel or flue *G'* is located below the plane of the receiving platform or furnace bottom and is controlled by a vertically sliding damper *H* operating in a channel *h* in the rear of the furnace wall. This damper may be conveniently raised through the instrumentalities of a cable or rope extending to the front of the furnace as indicated at *h'*. *I* designates the filling opening or throat which is preferably located directly over the center of the furnace as indicated more particularly in dotted lines Figure 2. The filling opening *I* is provided with a suitable cover *J*, which may be raised and permit the garbage carts to pass thereunder so that the contents may be properly dumped into the furnace through the opening *I*, the driveway of the furnace being indicated at *K*.

While generally the structure has been referred to above, it is to be understood that the essentials of the furnace are the relative positions of the grates, stoke hole and down-draft, with the central position of the receiving opening. It has been found, however, that the control in such a furnace is one of great importance, and therefore in the combination the damper *H* represents an important factor. In the operation the garbage carts are driven over the floor *K*, the top *J* being removed, and the contents are dumped into the opening *I* onto the receiving floor *E* at the middle of the furnace. In the first instance, or the starting, a fire is started on one of the grates, and the products of combustion, gases, etc., pass over the garbage heap located intermediate the down-draft opening, and the grate thereby drying the material and at the same time consuming the gases and preventing obnoxious odors entering the chimney. After a sufficient quantity of the garbage material has been dried it is raked onto the grate and the opposite grate may then be operated by raking the dried material thereon, or otherwise, and both fires used to quickly dry and consume the garbage. The stoke hole being centrally positioned between the grates both are easily accessible for the employment of the stoking iron to draw the dried material onto the grates until the same is entirely consumed. It may be stated here that the advantage of the down-draft with its association with the grates is that an action is acquired similar to that of the open hearth furnace, all of the liquid being evaporated, none being allowed to escape from the furnace bottom owing to the fact that the bottom is impervious and the various ledges or curb intercept the

passage of any materials into the down-take or onto the grates except that which has been dried may be pulled and drawn onto the grates over the curbing thereabout. The furnace bottom represents a large superficial area over which the garbage may be spread by stoking or otherwise, and as the material dries out the same may be drawn from any part onto the grates as above stated. The furnace is always a down-draft furnace, the products of combustion passing over the garbage and thereby the greater heat is employed to consume the gases and vapor as they pass towards the down-draft opening. By this means the furnace is prevented from smoking, a quick reduction of the garbage is accomplished in a most economical manner and by the employment of the two grates, when desired, the reduction of the garbage is accelerated and the amount of material which the furnace is capable of reducing in a given period of time is multiplied. One of the advantages of having intermediately disposed stoking openings is that of avoiding the necessity of opening the grate doors and further that of permitting the operator to maintain the proper condition on both grates through the single opening. By having the escape or outlet flue substantially on the plane of the floor the advantages heretofore stated are acquired and the fire and burning gases are brought into direct and intimate contact with the garbage on the floor. In actual practice it has been found that a minimum amount of coal and other fuel is necessary in this furnace, in fact it is only necessary to use a small amount of fuel to start the furnace and the dried material is employed for the incinerating purposes.

Having thus described this invention, what is claimed and desired to be secured by Letters Patent is:

1. An incinerating furnace having a material-receiving impervious bottom part, a pair of grates located at the front end of the furnace at opposite corners thereof, the bottom part having a forward portion extending between the grates, the furnace being provided with a stoke opening at the front thereof, centrally disposed between the grates adjacent said forward portion of the bottom for stoking both grates, the furnace also having a flue opening, and a filling opening for discharging the garbage onto the bottom part in line with the stoke opening.

2. An incinerating furnace having a material-receiving impervious bottom part, a down draft flue opening into the furnace adjacent the plane of the bottom part centrally of the sides of the furnace at the rear end thereof, a pair of grates located at the front end of the furnace at opposite cor-

ners thereof, the grates extending substantially in the horizontal plane of the bottom part, the furnace having a stoke opening between the pair of grates for stoking both grates, and a filling opening for distributing garbage substantially centrally of the bottom part, and an adjustable damper for governing the down draft flue.

In testimony whereof we hereunto affix

our signatures in the presence of two witnesses.
